(57) **CLAIM**

The ornamental design for a battery holder, as shown and described.

DESCRIPTION

FIG. 1 is a front perspective view of a battery holder of the present application;

FIG. 2 is a rear perspective view of the battery holder;

FIG. 3 is a front view of the battery holder;

FIG. 4 is a rear view of the battery holder;

FIG. 5 is a top view of the battery holder;

FIG. 6 is a bottom view of the battery holder;

FIG. 7 is a left side view of the battery holder;

FIG. 8 is a right side view of the battery holder;

FIG. 9 is a front perspective view of the battery holder showing a battery placed therein in phantom; and,

FIG. 10 is a rear perspective view of the battery holder showing a battery placed therein in phantom.

The broken lines shown in the drawings are included for the purpose of illustrating environmental structure and form no part of the claimed design.
